SMOKER'S PIPE

Walter Koster, New York, N.Y., assignor to S. M. Frank & Co. Inc., New York, N.Y., a corporation of New York

Application August 28, 1958, Serial No. 52,432

Term of patent 14 years

(Cl. D85—8)

I claim:

The ornamental design for a smoker's pipe, substantially as shown.
